UNITED STATES PATENT OFFICE.

JAMES H. HILL, OF ROCHESTER, NEW YORK, ASSIGNOR TO DEFIANCE
LANTERN & STAMPING COMPANY, OF ROCHESTER, NEW YORK, A
CORPORATION OF ONTARIO, CANADA.

LANTERN.

SPECIFICATION forming part of Letters Patent No. 717,680, dated January 6, 1903.

Application filed February 19, 1902. Serial No. 94,787. (No model.)

To all whom it may concern:

Be it known that I, JAMES H. HILL, a citizen of the Dominion of Canada, residing at Rochester, in the county of Monroe, in the State of New York, have invented certain Improvements in Lanterns, of which the following is a specification, reference being had to the accompanying drawings.

My invention relates to certain improvements in the construction of tubular lanterns, which improvements are fully described and illustrated in the following specification and the accompanying drawings, the novel features thereof being specified in the claims annexed to the said specification.

In the accompanying drawings, representing a lantern embodying my improvements, Figure 1 is a side elevation. Fig. 2 is a section on the line 2 2, Fig. 1, showing the parts below that line. Figs. 3 and 4 represent a modification.

My invention relates to improvements in the construction of the side-wire attachments of tubular lanterns, whereby the globe is automatically locked in both its depressed and elevated positions in a simple and efficient manner.

In the accompanying drawings, A represents the oil-reservoir; B, the burner; C C', the side tubes; D, the globe; E, the canopy, and F the vertical air-tube on which the canopy slides. The up and down movements of the globe and canopy are indicated by the full and dotted lines in Fig. 1. These parts are of any usual or preferred construction. The side wires H H' connect the canopy and the perforated plate or globe-rest I at the bottom of the globe. A spring-clip J encircles the top of the globe, being secured to the canopy on one side and provided on the other with an outwardly-turned projection L, by which the globe is inserted or removed. The side wires are attached to the canopy and the globe-rest in any suitable or preferred way, being bent inward at their lower ends, as indicated at K, to connect with the globe-rest. The side wires are bent outward and again inward, forming outwardly-projecting bows N N', Fig. 1. The guard P is fastened to the

oil-reservoir or air-chamber M, and extending upward encircles the globe and is provided with springs or yielding portions R R', which engage with the outer sides of the bows N N' and serve to lock the globe up or down. The springs R R' yield outward over the convex sides of the bows when the globe is raised or lowered, as indicated by the dotted lines in Fig. 1, and engage with either of the ends of the curved portions of the bows, so as to hold the globe in the elevated or depressed positions with sufficient resistance to sustain the globe during the operations of lighting, trimming the wick, &c., and also to secure the globe in place on the rest when the lantern is in use. The resistance to motion up or down is not so great but that it may be overcome by the application of a moderate degree of force, a thumb-piece T being soldered on the globe-rest for this purpose, if desired. At the same time the side wires and the globe are guided in their movements by the springs R R', since they encircle the outer sides of the bows, as shown in Fig. 2. In the construction shown the guard consists of two similar halves, each including one of the uprights U on each side of the globe, the circle or guard proper, P, and the springs R R', the uprights being secured together at their upper ends by a clip V; but any other suitable form of construction may be adopted.

The springs themselves may be rigid, the requisite elasticity being secured by the ring P. The combination of the springs and guard with the bowed side wires affords a simple and durable construction by which the globe is not only guided in its up and down movements, but is also held in either the elevated or depressed positions and protected from accident.

In Fig. 3 and in Fig. 4, which is a partial section of the globe and one side tube on the line 4 4, Fig. 3, I have represented a modification in which the guiding-spring R is attached to the side tube C and bears against the bowed portion N of the side wire H, as already described, to lock the globe in the different positions. The spring R is bent on itself or made double, so as to bear against the opposite sur-

faces of the wire, so as to serve as a guide to the same.

I claim—

1. The combination in a tubular lantern of 5 the reservoir, the outwardly-bowed side wires, and the guard around the globe consisting of the uprights supported on the reservoir on opposite sides thereof and the ring, the latter comprising yielding guards for the side 10 wires, as and for the purpose set forth.
2. The combination, in a tubular lantern, of the outwardly-bowed side wires and the yielding guides consisting of bent loops bearing on

opposite surfaces of the side wires, as and for the purposes set forth.

3. The combination, in a tubular lantern, of the outwardly-bowed side wires, and the guard for the globe, each comprising an upright, a curved portion and a yielding guide for the side wire, as and for the purposes set forth. 15 20

JAMES H. HILL.
